UNITED STATES PATENT OFFICE

109,672

DESIGN FOR A GRILLE FOR AUTOMOBILE RADIATOR

John Oswald, Lansing, Mich., assignor to General Motors Corporation, Detroit, Mich., a corporation of Delaware

Application October 25, 1937, Serial No. 72,395

Term of patent 3½ years

To all whom it may concern:

Be it known that I, John Oswald, a citizen of the United States and a resident of Lansing, county of Ingham, and State of Michigan, have invented a new, original, and ornamental Design for a Grille for Automobile Radiator, of which the following is a specification, reference being made to the accompanying drawings, forming a part thereof.

Figure 1 is a front elevational view of a grille for an automobile radiator showing my novel design.

Figure 2 is a side view of the novel design.
Figure 3 is a partial sectional view on the line 3—3 of Figure 1.

Figure 4 is a sectional view on the line 4—4 of Figure 2.

I claim:

The ornamental design for a grille for automobile radiator as shown.

JOHN OSWALD.
